SPHERAL POLYHEDRAL INTERLOCKING PUZZLE

Stewart T. Coffin, Old Sudbury Road,
Lincoln, Mass. 01773

Filed Apr. 14, 1972, Ser. No. 244,344

Term of patent 14 years

Int. Cl. D21—01

U.S. Cl. D34—15 M

The figure is a perspective view of a spherical polyhedral interlocking puzzle, showing my new design.

The design has regular dodecahedral symmetry, so that the views of all faces are identical.

I claim:

The ornamental design for a spherical polyhedral interlocking puzzle, as shown and described.
